INVENTOR

BY *Victor J. Evans*

ATTORNEY

L. B. Middleton
WITNESS:

UNITED STATES PATENT OFFICE.

JOHN W. McNAMARA, OF PERU, INDIANA.

SWAB.

Application filed June 26, 1920. Serial No. 392,064.

To all whom it may concern:

Be it known that I, JOHN W. McNAMARA, a citizen of the United States, residing at Peru, in the county of Miami and State 5 of Indiana, have invented new and useful Improvements in Swabs, of which the following is a specification:

This invention relates to means for lubricating reciprocating rods such as piston rods 10 and valve stem rods, the principal object of the invention being to provide a ring like container for the lubricant which surrounds the rod and is provided with openings in its inner periphery for permitting the lubricant to pass to the rod as the same is reciprocated through the container.

The purpose of my invention is to do away with the old style swab and oil cups which are now used to lubricate the rods 20 and packing.

This invention also consists in certain other features of construction and in the combination and arrangement of the several parts, to be hereinafter fully described, 25 illustrated in the accompanying drawings and specifically pointed out in the appended claims.

In describing my invention in detail reference will be had to the accompanying drawings 30 wherein like characters denote like or corresponding parts throughout the several views, and in which:

Figure 1 is a sectional view showing my invention applied to a piston rod.

Figure 2 is an end view with parts broken away of a slightly different form of the invention.

Figure 3 is a section on line 3—3 of Figure 2.

Figure 4 is an end view with parts broken away, of another form of the invention.

Figure 5 is a section on line 5—5 of Figure 4.

Fig. 6 is a sectional view of a modification.

Fig. 7 is a perspective view of one half of the sleeve.

Referring to Figure 1 the rod to be lubricated is shown at 1 and 2 indicates the ring like container for the lubricant which surrounds the rod. This container is suitably secured to a stationary part, such as the packing gland of a piston rod, so as to be immovable as the rod reciprocates through it. The inner periphery of the container snugly fits the rod, though loose enough to

prevent undue friction. The inner wall 3 of the container is provided with a number of inclined holes 4 which connect the interior of the container with the inner space in which the rod is located so that the lubricant may pass from the container on to the rod. The container is provided with a screw cap 5 by which it may be replenished with lubricant. The screw threaded opening in this cap engages the screw threads formed on the outer end of the inner wall 3 which is extended beyond the outer wall 6 of the container and said cap is formed with a thickened inner part 70 which fits between the inner and outer walls and forms a tight joint between the cap and container.

It will thus be seen that as the rod is reciprocated the lubricant will be drawn from the container through the holes 4 and will spread over the rod so as to thoroughly lubricate the same and will be carried by the rod into the packing gland and keep the packing lubricated.

In the form shown in Figures 2 and 3, the outer wall 7 is formed separate from the bottom 8 and the inner wall 9, this bottom and inner wall being formed integrally and the bottom being screw threaded to the outer wall 7. The part of the container consisting of the inner and bottom parts is divided into two parts so that these parts may be placed on the rod without having to slip them over the end of the rod. In this case the large outer wall is placed over the piston rod and the two halves forming the inner wall and the bottom are placed in position surrounding the piston and then the parts brought together and the bottom 90 screwed to the outer wall. Then the cap 10 is placed in position, this cap being similar to that shown in the first form. This construction is detachable where the piston rod has enlarged parts which would prevent 95 the form shown in Figure 1 from passing over them.

In the form shown in Figures 4 and 5, the container including the inner and outer walls and the bottom is divided into two 105 halves, each half having a pair of end walls 11, the end walls of each pair abutting the other end walls when the container is placed around the rod. The cap 12 in this form is also formed of two pieces with one piece 110 slightly larger than the other piece and this cap is provided with a groove 13 adjacent

its outer edge to receive the edge of the outer wall of the container. The two parts of the cap are held together by means of the spring semi-circular member 14 which is provided with a groove 15 to receive the outer periphery of the cap. This form of the device is more particularly adapted for air pump rods and rods where it is impossible or undesirable to pass the container over an end of the rod.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

20 1. A lubricator for reciprocating rods comprising an attaching base presenting a bore for the said rod, a perforated sleeve surrounding the bore, flange encircling the sleeve and spaced therefrom to provide an intervening space for lubricant, and a closure cap threaded on the outer end of the said sleeve and movable thereon into contact with the said flange to close the said space, said cap having a thickened portion fitting 25 between the sleeve and flange and providing a tight joint.

30 2. A lubricator for reciprocating rods

comprising a pair of complementary sections presenting perforated sleeve-sections between which the rod is accommodated and a 35 lubricant chamber surrounding the sleeve, the said sleeve having its outer end threaded, and a cap adjustable on the said sleeve for closing the said chamber, said cap having a threaded opening in which the threaded 40 end of the sleeve is confined, whereby the said complementary sections are held together.

3. A lubricator for reciprocating rods comprising a ring insertable over a rod and 45 threaded at one end, a sectional closure member for the threaded end of the ring, said member presenting attaching portions and integral perforated sleeve sections engageable around the rod and threaded shoulder 50 sections having threaded engagement with the threaded end of the said ring, said ring and sleeve sections being relatively spaced to provide a space therebetween for lubricant, said sleeve sections presenting a 55 threaded end beyond the said space, and a closure cap having threaded engagement with the threaded end of the sleeve sections and being adjustable thereon for engaging the said ring to close the said space, said 60 ring and said cap serving to hold the sections of the said closure together.

In testimony whereof I affix my signature.
JOHN W. McNAMARA.
